UNITED STATES PATENT OFFICE.

THOMAS H. ROSS, OF SYDNEY, NEW SOUTH WALES, ASSIGNOR TO JAMES B. DUKE, OF SOMERVILLE, NEW JERSEY.

DESIGN FOR A CAN-CAP.

SPECIFICATION forming part of Design No. 30,764, dated May 16, 1899.

Application filed May 4, 1898. Serial No. 679,734. Term of patent 14 years.

To all whom it may concern:

Be it known that I, THOMAS H. ROSS, a subject of Her Majesty the Queen of Great Britain, residing at Sydney, New South Wales, have invented and produced a new and original Design for Can-Caps, of which the following is a specification, reference being had to the accompanying drawings, forming a part thereof.

10 In the accompanying drawings, Figure 1 is a perspective view of a can-cap embodying the design. Fig. 2 is a transverse vertical sectional view, and Fig. 3 is a plan view.

15 As shown in the drawings, the leading or material feature of my design consists of a double flange A, projecting from the edge of the crown B at substantially right angles to

the main plane of the crown, the said flange consisting of two members C C, connected by the curved piece D, and the said members 20 having coinciding screw-threads E E bent therein.

Having thus described my invention, what I claim as new, and desire to secure by Letters Patent, is—

25 The design for a can-cap substantially as herein shown and described.

In testimony whereof I hereunto affix my signature in the presence of two witnesses.

THOS. H. ROSS.

Witnesses:

J. CHR. DUSEL,
JAMES M. DIXON.
